G. BODEN

DOUBLE POINTED PIN FASTENER

Filed May 28, 1927

Patented Nov. 15, 1927.

UNITED STATES PATENT OFFICE.

GEORGE BODEN, OF WATERBURY, CONNECTICUT, ASSIGNOR TO SCOVILL MANUFACTURING COMPANY, OF WATERBURY, CONNECTICUT, A CORPORATION OF CONNECTICUT.

DOUBLE-POINTED-PIN FASTENER.

Application filed May 28, 1927. Serial No. 194,946.

The object of this invention is to provide a pin-attached snap-fastener member, either socket or stud, and also a capped pin, especially for use in attaching covers to the upholstered parts of automobiles.

The invention consists of a plate having a perforation, such as a slot or two holes, at its top, to receive the limbs of a double-pointed pin, which has a looped head, and means, such as a tongue, at its bottom to engage the looped head, as I will proceed now to explain and finally claim.

In the accompanying drawings illustrating the invention, in the several figures of which like parts are similarly designated, Figure 1 is a front elevation, Fig. 2 is a rear elevation, with one of the limbs of the pin broken out, Fig. 3 is a side elevation, Fig. 4 is a longitudinal section, and Fig. 5 is a cross-section on line 5—5 of Fig. 3, illustrating a socket plate slotted to engage the pin head. Fig. 6 is a front elevation, Fig. 7 is a rear elevation with one of the limbs of the pin broken out, Fig. 8 is a side elevation, Fig. 9 is a longitudinal section, and Fig. 10 is a cross-section on line 10—10 of Fig. 8, illustrating a plate having separate holes for the individual members of the pin head. Fig. 11 is a fragmentary side view illustrating the invention as applied to a stud member of a snap fastener. Fig. 12 is a fragmentary rear view and partial section, and Fig. 13 is a fragmentary side view illustrating the invention applied to a capped pin.

The doubled-pointed pin herein shown, may be of substantially the construction illustrated in the patent of Boden, King and Chapman, No. 1,604,801, granted October 26, 1926, and comprises the limbs 1, the pointed ends 2, and the looped head 3 having the humped portions 4 and the bend 5, made of suitable wire, and the looped end bent over substantially parallel with the limbs and having the side members 6.

7 is a plate of any suitable contour and outline, having at its top a rearwardly turned flange 8 provided with a transverse slot 9. The bottom of the plate is provided with the flange 10 having a tongue 11, both projecting rearwardly from the plate, the flange 10 being of substantially the same width as the slotted flange 8. The plate is also provided with an opening 12 of such

dimensions that the sides 6 of the looped head cross the said opening and are free to exert resiliency to engage a stud member, such as that shown applied to a pin in Fig. 11.

The pin is applied to the plate by passing its loop 10 through the slot 9, with its bend extending in the direction of the flange 10 and next to the back of the plate, and thereupon the tongue 11 is bent over the bend 5 so as to secure that end of the pin to the plate, the limbs of the pin being adjacent to the edges of the flange 10 on opposite sides of the tongue 11.

As shown by dotted lines in Fig. 4, the tongue 11 extends off from the flange 10 until after the looped head has been positioned in the plate, and then it is bent over on the bend 5, as indicated in full lines in said Fig. 4.

Instead of having the upper flange of the plate made with a slot, said flange, designated 13 in the form shown in Figs. 6 to 10, has the two holes 14 through which the inverted ends of the limbs of the pin are inserted and then turned over so that the looped end of the pin lies against the back of the plate 15 while the limbs of the pin extend across the edge of the flange 13 and thence downwardly. Instead of the bottom flange such as used in the previously described form, I may use in this connection a tongue 16 which stands off from the plate, as indicated in dotted lines, Fig. 9, and then is bent on the bend 5 of the pin, as shown in Figs. 7, 8 and 9, to retain the pin in engagement with the plate.

In the construction shown in Figs. 6 to 10, the plate 15, may have the opening 17 which corresponds in function and operation to the opening 12 of the form shown in Figs. 1 to 5, to engage a stud member.

In Fig. 11 I show a construction in which a plate 18 may be formed with the stud member 19. In this form the pin may be attached to the plate either by the slot features shown in Figs. 1 to 5 or the holes feature shown in Figs. 6 to 10, the plate having the upper perforated flange 20 and the lower bend-engaging flange 21.

As shown in Figs. 12 and 13, a solid or imperforate flanged cap 22, may be secured to a pin either by the slot expedient, such as shown in Figs. 1 to 6, and designated 23 in

Fig. 12, or the holes expedient, such as shown in Figs. 6 to 10, above described, and the lower clamping tongue 24.

It will be understood that when the plate is made with the opening in front, it is used as a socket member of a snap fastener. The device is adapted to be applied by sticking the pin limbs in the upholstered part or other part to which it is applied, while the complementary stud member is riveted or otherwise fixedly applied to a cover which is to be attached to the upholstered or other part. So also when the pin end carries the stud member of a snap fastener, as in Fig. 11, this stud member would be stuck in the upholstered part, while the complementary socket member would be suitably attached to the cover.

The cap pin, shown in Figs. 12 and 13, which is neither socket member nor stud member, is used to pin the cover to the upholstered part directly.

Referring to the construction shown in Figs. 1 to 5, it is to be noted that the looped head should be of such size as to fit freely in the slot so as not to interfere with the resiliency of the sides 6 for effectively engaging the stud.

It will also be noticed that the engagement of the headed pin with the plate or cap, is such as to preclude relative movement of the plate or cap and the pin.

Variations in details of construction are permissible within the principle of the invention and the claims following; and it is also noted that by the use of the term "front piece" in the claims, I intend to include not only the socket member and the stud member, but also the cap member; and by the term "perforated" in the claims, I intend to include both the slot and the holes for the pin.

What I claim is:—

1. A double-pointed pin fastener, having a front piece, and a double-pointed pin provided with a looped head, the front piece perforated to receive the looped head of the

pin, and a tongue at the end opposite the perforated part to engage the looped head.

2. A double-pointed pin fastener, having a front piece, and a double-pointed pin provided with a looped head, the front piece having a rearwardly extending flange provided with a transverse slot through which the looped head is passed so as to lie against the back of the front piece, and means to engage the bottom of the looped head to hold the pin in fixed relation to the front piece.

3. A double-pointed pin fastener, having a front piece, and a double-pointed pin provided with a looped head, the front piece having a rearwardly extending flange provided with a transverse slot through which the looped head of the pin is passed so as to lie against the back of the front piece, and another flange opposite the first-mentioned flange adjacent to which the limbs of the pin extend and a tongue on said last-mentioned flange adapted to engage the looped head to hold the front piece and the pin in fixed relation.

4. A double-pointed pin fastener, having a front piece, and a double-pointed pin provided with a looped head, the front piece perforated to receive the looped head of the pin, and a tongue at the end opposite the perforated part to engage the looped head, said front piece having a snap fastener element.

5. A double-pointed pin fastener, having a front piece, and a double-pointed pin provided with a looped head, the front piece perforated to receive the looped head of the pin, and a tongue at the end opposite the perforated part engaging the looped head, and said front piece having an opening straddled by the members of the looped head of the pin and serving as a socket member of a snap fastener.

In testimony whereof I have hereunto set my hand this 25th day of May A. D. 1927.

GEORGE BODEN.
